CLOCK CASE

Filed Sept. 29, 1923

Patented Dec. 25, 1923.

Des. 63,674

UNITED STATES PATENT OFFICE.

RICHARD H. WHITEHEAD, OF NEW HAVEN, CONNECTICUT, ASSIGNOR TO NEW HAVEN CLOCK CO., OF NEW HAVEN, CONNECTICUT, A CORPORATION.

DESIGN FOR A CLOCK CASE.

Application filed September 29, 1923. Serial No. 7,363. Term of patent 14 years.

To all whom it may concern:

Be it known that I, RICHARD H. WHITEHEAD, a citizen of the United States, residing at New Haven, in the county of New Haven and State of Connecticut, have invented a new, original, and ornamental Design for a Clock Case, of which the following is a specification, reference being had to the accompanying drawing, forming part thereof.

Fig. 1 is a face view of a clock case showing my new design.

Fig. 2 is a side view of the same.

I claim:

The ornamental design for a clock case as shown.

RICHARD H. WHITEHEAD.

Witnesses:

CATHERINE A. O'NEIL,
ROSE McKEON.
